United States Patent Office.

EDWARD SEMPLE, OF CHICAGO, ILLINOIS.

Letters Patent No. 74,723, dated February 18, 1868.

IMPROVEMENT IN TRUNKS.

The Schedule referred to in these Letters Patent and making part of the same.

TO ALL WHOM IT MAY CONCERN:

Be it known that I, E. SEMPLE, of the city of Chicago, in the county of Cook, and State of Illinois, have invented new and useful "Improvements in Trunks;" and I do hereby declare that the following is a full and exact description thereof, reference being had to the accompanying drawings, making part of this specification.

The nature of my invention consists in providing the corners of the cover and of the box of trunks with metallic plates, so arranged that when the trunk is closed the plates hold the cover and the box together, preventing any lateral motion of the cover, and stiffening the entire frame of the trunk, each plate being provided with a suitable locking-device.

To enable others skilled in the art to make and use my invention, I will proceed to describe its construction and operation.

A A are the angle-plates, made of sheet or cast metal, and riveted to the front corners of the box B of the trunk. The side halves of these plates are provided with loops *a a*, which loops may be cut out of the body of the plates themselves, or cast in one piece with them, or made or cast separately, and secured by rivets to the said plates. C C are the angle-plates for the cover D of the trunk, made in the same way and of the same material as the plates A A, their side halves being provided with knives or bars *b b*, made of one piece with the plates, or made separately and then riveted to them. Said knives or bars are for the purpose of entering loops *a a* of the angle-plates of the box, when the trunk is closed, and thus fastening and strongly holding together the box and the cover of the trunk. For locking the trunk, the front halves of the cover angle-plates may be provided with a hasp, a hook, or any other suitable arrangement, and the front halves of the box angle-plates provided with staples for padlocks, or with any other locks secured to them, they being arranged like face-plates to those locks.

The advantages of the trunk angle-plates, arranged as above described, are these, that with them the connection between the box and the cover is perfect, and any lateral motion of the cover is prevented; besides that, the angle-plates stiffen the whole frame of the trunk and make the upper corners of the box, as well as those of the cover, where generally the iron breaks, strong and durable.

What I claim as my invention, and desire to secure by Letters Patent, is—

The angle-pieces A, provided with the loops *a*, in combination with the angle-pieces C, provided with the lugs *b*, when arranged for operation, in connection with a trunk or similar article, substantially as described.

EDWARD SEMPLE.
